UNITED STATES PATENT OFFICE

2,562,071

FLUORESCENT LAMP CHANGING TOOL

Lafe Stueland, Alameda, Calif.

Application July 6, 1948, Serial No. 37,179

3 Claims. (Cl. 294—21)

1

The invention relates to tools designed for detachable engagement with a fluorescent lamp tube, or the like, for facilitating the insertion and removal of such tubes in and from their socket mountings.

An object of the present invention is to provide a fluorescent lamp changing tool of the character described which is designed for simple and ready grasping and support of the tube whereby the latter may be conveniently and precisely positioned by the user into engagement with the tube mounting sockets for the terminals at the opposite ends of the tube, together with means for readily rotating the tube for securing of its terminals in the mounting sockets, and wherein the tool will function in a reverse manner in clasping a tube desired to be removed from its mounting and in rotating such tube to a released position.

Another object of the invention is to provide a fluorescent lamp changing tool of the character above which will firmly grasp the tube being handled by the tool for safe movement into position in lamp fixtures remotely situated with respect to the user and wherein the lamp gripping portions of the tool closely fit the periphery of the tube so as to permit the mounting of the tube in a fixture having a reflector or other fixture part in close proximity to the tube when in mounted position.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is an end elevation of a fluorescent lamp changing tool constructed in accordance with the present invention.

Figure 2 is a cross-sectional view of the tool taken substantially on the plane of line 2—2 of Figure 1.

Figure 3 is a cross-sectional view of the tool taken substantially on the plane of line 3—3 of Figure 2.

The tool, illustrated in the accompanying drawing, includes a substantially U-shaped member 6, having an elongated generally rectangular base 7, and a pair of upstanding generally parallel sides 8 and 9 extending from the base in planes substantially perpendicular thereto. Journalled

2 for rotation within the member 6, in spaced substantially parallel relation to the base 7, is a friction roller 11, preferably formed of relatively soft compressible rubber or like material, supported 5 with its axis of rotation generally parallel to the planes of sides 8 and 9. The normal spacing of sides 8 and 9 is somewhat less than the diameter of a standard fluorescent light tube 12 with which the tool is adapted for use and in operation the 10 sides 8 and 9 are resiliently spread, as illustrated in Figure 3, so as to embrace opposed peripheral portions of the tube. As will be best seen from Figures 1 and 3, the sides 8 and 9 are bowed adjacent their upper ends 13 and 14 to provide opposed concave shoulders 16 and 17 which are formed and located relative to the diameter of tube 12 and the remainder of the member 6 so as to resiliently engage opposed peripheral portions 15 of the tube above the center thereof so as to firmly 20 clasp the tube between the shoulders and the periphery of roller 11 to provide a three-point gripping of the tube. To facilitate insertion of the tube into position within the clasp, the outer ends 13 and 14 of sides 8 and 9 are preferably 25 reversely curved with respect to shoulders 16 and 17 to thereby cause an automatic spreading of the sides upon placing of the ends 13 and 14 against the periphery of a tube 12.

In accordance with the present invention, 30 means is provided exteriorly of the clasp member 6 for rotating the roller 11, so as to thereby rotate tube 12 into a secured position in its socket mountings in effecting the insertion of the tube, or contrawise, a rotation of the tube to a released position with respect to its mounting sockets on removal of the tube. This means here consists of a hollow shaft 18 journalled for rotation in a bearing sleeve 19 fixed to and depending from the base 7. The inner end 21 of shaft 18 is connected 35 to roller 11 by means of a flexible drive 22 and projects at its outer end 23 from the bearing sleeve 19 for engagement with an extension part 24. The latter is preferably detachably connected as by means of a removable pin 26 or cotter key 40 and may be of any desired length for positioning of the device at remote distances from the user. Several different lengths of part 24 may be provided for reaching tubes in fixtures at different elevations.

45 Various types of drive connection may be used between shaft 18 and roller 19 so as to afford a remote operation of the roller. In the present device, and as illustrated in the accompanying drawing, the roller 11 is provided with an axial bore 27 tightly fitted upon the exterior of a

helical spring 28 which is, in turn, supported on an axially extending rod 29. One end 31 of the rod 29 is bent at substantially right angles to the axis of the roller and is positioned through an aperture in the base 1 and secured thereat by nuts 32 and 33 threaded on to the end 31 on opposite sides of the base. The opposite end 34 of the rod is curved to extend from the center portion of the rod on which the roller is mounted into the center of shaft 18 so as to locate therein one end 36 of the spring 28. The spring end 36 has a pressed fit within the interior of shaft 18 anchoring the spring and shaft for joint movement. In this manner rotary movement of shaft 18 will be transmitted through spring 28 to roller 11, it being noted that the axes of the shaft and the roller are at substantially right angles to each other.

In operation to remove a fluorescent lamp tube from its fixture, the clasp member 9 may be elevated to the fixture by means of the handle extension 24 so as to place the open upper end of the clasp member against the bottom side of the tube to be removed. By pressing the open side of the clasp against the tube, sidewalls 8 and 9 will be resiliently spread and sprung on to the tube periphery, as illustrated in Figure 3 so as to firmly embrace the tube and grip the tube against the roller 11. The sidewalls 8 and 9 are preferably formed of spring metal or other resilient material, having a relatively low coefficient of friction, so as to permit ready turning of the tube within the clasp member. On the other hand, the roller 11 is preferably formed of a material, such as rubber, having a relatively high coefficient of friction so as to firmly grip the tube for joint rotation of the tube and the roller. Accordingly, after attachment of the clasp member to the tube, as above described, the operator merely needs to turn the handle extension 24 so as to transmit a rotary movement to the roller 11 and the tube so as to free the tube from its mounting sockets. Thereafter, the tube may be safely lowered to the operator while it is firmly gripped in the clasp member thereby preventing accidental dropping and breaking of the tube. When the device is used for installing a tube, the above operation is substantially reversed, that is, the tube is first inserted in the clasp member 6, then elevated to its mounting sockets in the light fixture, and then the handle part 24 is rotated so as to rotate the lamp terminals into locked engagement in the sockets. In the operations above described, it will be noted that the clasp member 6 closely embraces the tube, particularly at the upper end thereof, so as to permit the placing of the tube in close proximity to the reflector or to the fixture parts. In this connection it will be particularly noted that the upper ends 13 and 14 extend but a very short distance from the periphery of the tube engaged within the clasp member.

I claim:

1. A tool for detachably engaging a fluorescent lamp tube or the like for insertion and removal of the tube in and from its socket mountings comprising, a tube engaging and supporting member,

a roller mounted on said member for rotation about an axis generally parallel to the axis of a tube in the supported position thereof, said member having a spring part formed to resiliently engage the periphery of a tube and to resiliently clasp said tube between said part and said roller for joint rotation of said tube and roller, a handle connected to and freely rotatable relative to said member, and drive means connected to said roller and said handle for turning said roller in either direction on rotation of said handle, said spring part having a relatively low coefficient of friction to permit ready turning of said tube periphery thereagainst and said roller having a relatively large coefficient of friction to grip said tube periphery for joint rotation of said tube and roller.

2. A tool for insertion and removal of fluorescent light tubes and the like comprising, a U-shaped clasp member of spring material having a base and a pair of sides extending therefrom in generally parallel relation substantially perpendicular to said base, a roller mounted for rotation within said member adjacent said base and along an axis of rotation substantially parallel to the planes of said sides, rotatable drive means connected to said roller and carried by said member and manually engageable exteriorly of said member for turning said roller, and flexible means interconnecting said drive means and said roller whereby the latter may be selectively rotated in either direction upon rotation of said drive means, said sides being formed to resiliently clasp the periphery of a tube to be handled by the tool and to urge said periphery into engagement with said roller for rotation therewith.

3. A tool for detachably engaging a fluorescent lamp tube or the like for insertion and removal of the tube in and from its socket mountings comprising, a U-shaped clasp member of spring metal having a base and a pair of sides extending therefrom in generally parallel relation substantially perpendicular to said base, a friction roller of compressible rubber-like material mounted for rotation in said member in spaced substantially parallel relation to said base and along an axis of rotation located between and substantially parallel to the planes of said sides, a manually engageable part journaled for rotation in said base and extending exteriorly thereof about an axis substantially perpendicular to said base, and a flexible drive means connecting said part and said roller to effect rotation of said roller relative to said member on rotation of said part, said sides being formed for resilient spreading to clasp the periphery of said tube between said sides and said roller for joint rotation of said tube and roller.
